UNITED STATES PATENT OFFICE.

CHARLES E. KLOPFER, OF WASHINGTON, DISTRICT OF COLUMBIA.

CARBON REMOVER FOR SPARK PLUGS.

Application filed July 12, 1922. Serial No. 574,418.

To all whom it may concern:

Be it known that I, CHARLES E. KLOPFER, a citizen of the United States, residing in the city of Washington, and District of Columbia, have invented certain new and useful Improvements in Carbon Removers for Spark Plugs, of which the following is a specification, reference being had therein to the accompanying drawing.

10 This invention relates to a method and apparatus for cleaning spark plugs by burning the carbon therefrom, the object being to provide an apparatus by means of which the carbon can be quickly removed from the 15 plug without injuring the same in any way, thereby overcoming the difficulties now existing with other devices, such as sand blast devices.

A still further object of the invention is to 20 provide an apparatus in which a movable spark plug holder is provided so that it can be adjusted in respect to the oxygen nozzle to allow the apparatus to accommodate various 25 lengths of spark plugs and to allow the plug to be moved to and fro from the oxygen nozzle so that the carbon will be thoroughly removed from the spark plug.

Another and further object of the invention is to provide an apparatus in which the 30 fuel used for burning the carbon from the plug can be ignited electrically or by a match similar to the method now employed in burning carbon from cylinders.

A still further object of the invention is 35 to provide an apparatus in which the spark plug holder is so constructed that when the spark plug is in position and the carbon is being burnt therefrom, the sparks are prevented from flying as the end of the plug is disposed within a chamber which is provided with vents so disposed that the sparks, if any escaping, pass upwardly and are arrested before they scatter from the holder.

Another and further object of the invention is to provide a holder in which the plug 45 closes the chamber and is held in position within the apparatus by the weight of the plug so that the same is allowed to yield under pressure acting as a safety valve.

50 Other and further objects and advantages of the invention will be hereinafter set forth and the novel features thereof defined by the appended claims.

In the drawings,

55 Figure 1 is a side elevation, partly in sec-

tion, of an apparatus for carrying out my improved method of burning carbon from spark plugs; and

Figure 2 is a vertical section through a portion of the apparatus showing the construction of oxygen nozzle and holder and the manner of mounting the same.

In the drawing 1 indicates a box in which are disposed batteries 2 and a coil 3 forming substantially a sparking device which may be of the ordinary construction now in use for testing spark plugs or of any other suitable construction.

Arranged on the box 1 is a base 4 which is provided with a bore forming a conduit 5 in one end of which is secured a nipple 6 to which is connected a flexible tube 7 adapted to extend from an oxygen tank not shown.

Mounted within the other end of the conduit is the nipple of a valve 8 for controlling the supply of oxygen. The casing of the valve is provided with a threaded nipple 9 over which is arranged a tubular nozzle 10, the lower end being seated on an annular flange 11 formed on the valve casing, said tubular nozzle having a cap 12 disposed therein adjacent its upper end provided with jets 13 which are preferably annularly arranged so as to direct the oxygen onto the plug as will be later described.

Slidably mounted on the tubular nozzle is a spark plug holder 14 which is provided with a tubular portion 15 fitting snugly around the tubular nozzle 10, said tubular portion being enlarged as shown at 16 having a threaded bore in which is mounted a screw 17 which works in a vertical groove 18 formed in the tubular nozzle for limiting the upward movement of the spark plug holder 15 on the nozzle. The nozzle is surrounded by a coil spring 19 which normally holds the spark plug holder in the position shown in Figures 1 and 2, said holder being provided with a handle 20 so as to allow the holder to be moved up and down on the nozzle so as to adjust the plug in respect to the oxygen supplying nozzle and while I have shown the holder adjustable in respect to the nozzle, I am aware that the holder can be fixed and the nozzle adjusted in respect to the holder and therefore I do not wish to limit myself to the construction of apparatus as herein shown as I am aware that various changes can be made without departing from the spirit of my invention.

110

The holder is provided with a chamber 21 having a reduced neck portion 22 adapted to receive the plug, the upper end of the holder being provided with an annular 5 flange 23 and radiating ribs 24. The upper portion of the chamber is provided with passages 25 extending from the shoulder formed by the reduced portion so as to form vents for the chamber 21.

10 The tubular portion 15 of the holder is provided with an opening 26 which is normally held by the spring above the upper end of the nozzle and through which a match is adapted to be inserted for igniting 15 the fuel of the plug as will be later described.

In Figure 1 I have shown a spark plug 27 disposed in position within the holder to be cleaned having its electrode connected to a terminal 28 of the coil 3 by a wire 3', 20 said coil and battery being in circuit with a press button 29 so that by pressing the button, a spark will be formed so as to ignite the fuel of the plug as oxygen is supplied thereto and while I have shown an electrical 25 device of this nature, I am aware that various other constructions of electrical ignition devices can be used but I have found in practice that by mounting my improved apparatus on an ordinary spark testing device, 30 the carbon and oxygen can be ignited and it will be noted that in the construction shown I also show an opening through which a 35 match can be inserted for igniting the fuel and by the particular construction of apparatus shown after the fuel has been ignited with a match, the holder is pressed downwardly so as to close the ignition opening.

In carrying out my method I preferably 40 dip the spark plug in a fuel such as gasoline and then insert the same in the holder in the position shown in Figure 1. The valve 8 is then opened so as to supply oxygen to the nozzle 10 and by inserting a match through the opening or by pressing the button 29, the carbon is ignited on the spark 45 plug and by moving the holder to and from the plug, the carbon will be thoroughly burnt from the terminals and porcelain without injuring the same in any way.

50 By constructing the nozzle in the manner shown, I am able to move the plug downwardly in close proximity to the end of the nozzle so that the jets of oxygen will be applied to the interior of the plug so as to 55 burn the carbon therefrom without applying an excess of heat to the porcelain.

While I have shown one form of apparatus for carrying out my method, I am aware that various other forms of apparatuses can be used but I have found that 60 by providing an apparatus with a chamber to which oxygen is supplied and in which the portion of the plug to be cleaned is placed, I am able to thoroughly burn the 65 carbon from the plug.

What I claim is:—

1. The method of cleaning spark plugs by burning the carbon therefrom consisting of coating the plug with a fuel, supporting the plug in a vertical position, directing a jet 70 of oxygen onto the plug from beneath and igniting the fuel to burn the carbon therefrom.

2. The method of cleaning spark plugs by burning the carbon therefrom consisting in 75 first coating the plug with a fuel, then placing the plug in a holder provided with a chamber, directing into said chamber a jet of oxygen and igniting the fuel to burn the carbon from a portion of the plug within 80 the chamber.

3. In a device of the kind described, the combination with an oxygen nozzle, of a holder movably mounted in respect to said nozzle having a chamber to receive a spark 85 plug and electrical means for producing a spark within said chamber.

4. In a device of the kind described comprising an oxygen supplying nozzle and a holder, said holder and nozzle being movably mounted in respect to one another, said holder having a chamber provided with an open neck portion adapted to receive a spark plug, said chamber having vents and means for controlling the supply of oxygen to said 90 nozzle.

5. An apparatus for burning carbon from spark plugs comprising a base having a bore having a nipple at one end to which is adapted to be connected a flexible tube leading from an oxygen tank, a valve having a nipple secured in the other end of said bore, a nozzle secured to said valve, a holder slidably mounted on said nozzle having a chamber adapted to receive a spark plug 100 and means for limiting the movement of said holder on said nozzle.

6. An apparatus for cleaning spark plugs comprising a base having an oxygen nozzle disposed vertically thereon, a holder slidably mounted on said nozzle provided with a chamber having an open neck portion surrounded by a series of vents, a spring surrounding said nozzle for supporting said holder, said chamber having an opening at 115 its lower end, said opening being adapted to be closed by said nozzle when said holder is moved downwardly.

7. An apparatus for burning carbon from spark plugs comprising an oxygen supplying nozzle and a spark plug holder, one being movably mounted in respect to the other, said holder having a chamber to receive the portion of the spark plug to be cleaned and means for igniting the carbon of the spark 120 plug.

8. A device for burning carbon from spark plugs comprising a holder having a chamber provided with vents and a reduced neck portion into which a spark plug is 130

adapted to be inserted, means for directing a jet of oxygen into said chamber, and means for controlling the supply of oxygen.

9. In a device of the kind described, the combination with an oxygen nozzle, of a holder slidably mounted on said nozzle provided with a chamber adapted to receive a spark plug, said chamber being provided with vents and a handle for moving said holder in respect to said nozzle.

10. In a device of the kind described, the combination with a tubular nozzle having a cap adjacent its upper end provided with a series of jets, of a holder slidably mounted on said nozzle having an opening through which a match can be inserted, said holder being provided with a chamber having an annular flange at its upper end and provided with a series of vents and means for limiting the movement of said holder on said nozzle.

11. A spark plug burner comprising a spark plug holder having a chamber provided with a reduced neck portion to receive a spark plug, said chamber being provided with vents, an oxygen nozzle extending into said holder, said nozzle and holder being movably mounted in respect to one another.

12. The method of cleaning spark plugs by burning the carbon therefrom consisting in first dipping the plug in a fuel and then inserting the plug into a chamber, then di-

recting a jet of oxygen into said chamber and finally igniting the fuel of said plug for burning the carbon therefrom.

35

13. A device for burning carbon from spark plugs comprising a holder having a chamber provided with an open neck portion to receive a spark plug, said chamber being provided with a series of vents at its upper end and an opening at its lower end through which a match can be inserted, a tubular nozzle extending into said holder having a cap adjacent its upper end for directing the series of jets of oxygen onto the plug within said chamber, said holder and nozzle being movably mounted in respect to one another and means for limiting the movement of said holder in respect to said nozzle.

14. In a device of the kind described, the combination with a nozzle, of a holder arranged above said nozzle having a chamber to receive a spark plug and means for producing a spark within said chamber.

15. A device of the kind described, comprising a chamber provided with vents and an open top to receive a spark plug, means for directing a jet of oxygen into said chamber from beneath and means controlling the supply of oxygen.

60 In testimony whereof I hereunto affix my signature.

CHARLES E. KLOPFER.
